UNITED STATES PATENT OFFICE.

LYMAN LUCE AND CASSIUS M. WILDER, OF KINGSVILLE, OHIO, ASSIGNEES
TO KINGSVILLE WROUGHT IRON FENCE COMPANY, OF SAME PLACE.

FENCE-POST.

SPECIFICATION forming part of Letters Patent No. 247,732, dated September 27, 1881.

Application filed August 16, 1881. (Model.)

To all whom it may concern:

Be it known that we, LYMAN LUCE and CASSIUS M. WILDER, of Kingsville, in the county of Ashtabula, and in the State of Ohio, have 5 invented certain new and useful Improvements in Fence-Posts; and we do hereby declare that the following is a full, clear, and exact description thereof, reference being had to the accompanying drawings, and to the letters of reference marked thereon, making a part of this 10 specification.

This invention relates to certain improvements in fence-posts; and it has for its objects to provide certain means whereby the posts 15 may be supported and adjusted vertically and laterally, as more fully hereinafter specified. These objects we attain by the devices illustrated in the accompanying drawings, in which—

20 Figure 1 represents a perspective view showing our invention complete, and Fig. 2 a detached detailed perspective view.

The letter A indicates a base, constructed preferably of metal, supporting an upright, B, 25 constructed of a flat strip of metal, bent as indicated at C, so as to form a flat bearing for the fence-post D. The base is slotted longitudinally at E, in which slot the lower end of the fence-post D is loosely secured. The said

post is slotted at F, and has secured to it a 30 slide, G, by means of a screw-bolt, H, passing through a slot, K, in the standard in such manner that the post may be adjusted either laterally or vertically with respect to said standard and securely held in such adjusted position. The base A may be secured in any desired position to any suitable support. 35

Having thus described our invention, what we claim, and desire to secure by Letters Patent, is—

40 In combination with the base and its standard, constructed as described, the standard being provided with a horizontal slot and the base with a longitudinal slot, the slotted fence-post setting in the slot in the base, and the slide 45 secured to the post by means of a clamping-screw passing through the slots in the post and standard and the clamping-nut on said screw, whereby the post may be adjusted vertically and laterally, substantially as specified. 50

In testimony that we claim the foregoing we have hereunto set our hands this 28th day of July, 1881.

LYMAN LUCE.
CASSIUS M. WILDER.
